Patented Sept. 3, 1929.

UNITED STATES PATENT OFFICE.

ARVID P. EKVALL, OF WORCESTER, MASSACHUSETTS, ASSIGNOR TO ECONOMIC MACHINERY COMPANY, OF WORCESTER, MASSACHUSETTS, A CORPORATION OF MASSACHUSETTS.

BOTTLE-FEED MECHANISM.

Application filed February 27, 1928. Serial No. 257,313.

This invention relates to a new type of bottle feeding mechanism and is especially adapted for use in connection with the disclosure that is made in my prior Patent No. 5 1,630,235, granted May 24, 1927.

In my former patent, the bottles are merely pushed or forwardly impelled by a reciprocatory head or member and deposited on to the conveyor that carries the bottles in a step by step manner through the machine. Such a feed has been found, in some respects, to be defective or objectionable owing to the fact that the bottles have occasionally canted or twisted out of their correct position, when 15 finally delivered to the step by step conveyor. In some instances the bottle has been crushed or broken by the pusher head in jamming the canted bottle against the side wall of the conveyor, then again they have 20 been broken by the first advancing movement of the conveyor when the bottle is not correctly positioned thereon.

It is, therefore, the main object of this 25 present improvement to overcome the above-mentioned disadvantages by providing a grip or clamp which acts in conjunction with the pusher element to firmly hold the bottle against any twisting or canting and to finally deposit said bottle in a correct position onto 30 the step by step conveyor.

Another object of the invention resides in 35 the novel manner of receiving, clamping and finally releasing the bottle, all of which is accomplished by the peculiar coaction had between the bottle grip and the pusher head.

It will, of course, be readily understood 40 that these and other objects will present themselves to persons skilled in this line of structure when the following specification is read in connection with the accompanying drawings, and I hold it within my rights 45 to make certain changes or deviations therefrom without sacrificing any of the spirit of the invention, so long as they fall within the terms set forth in the annexed claims.

In the attached drawings, like parts 50 through the several views are indicated by similar letters of reference, wherein

Figure 1 is an end elevation showing a 55 bottle in clamped position and ready for transfer.

Figure 2 is a front elevation of the device.

Figure 3 is a plan view of the complete 60 mechanism, and

Figure 4 is a detail view relating to the cam and lever arrangement for accomplishing the desired coactive movements between the grip finger and the pusher head.

Referring more in detail to the drawings, 60 1 indicates the legs or standards upon which the base 2 of the machine is supported. Upon the base 2 and extending to the right, as shown in Figure 3, is a conveyor belt or band 3 travelling over rollers 4 and driven 65 in any suitable manner. Along the lateral sides of the belt or band 3 are parallel bars 5-5 which constitute guides to retain the bottles on to the conveyor 3. These guides are adjustably mounted so as to accommodate bottles of various sizes. Also upon the base 2 and extending to the left, as seen in Figure 3, is a step by step conveyor 6 having side rails 7-7, the details of which are covered in my prior Patent No. 1,630,235. 70 This step by step conveyor is arranged in offset relation with respect to the conveyor 3 and has its end in overlapping relation to the latter. The bottles that are presented at the end of the conveyor 3 are to be delivered or transferred on to the step by step conveyor 6 for subsequent treatment at the several stations in the machine and it is at 75 the point of transfer from the conveyor 3 to the conveyor 6 that the present improvement is directed.

At right angles to the exit end of the conveyor 3 is positioned a vertically extending plate 8 on which is mounted a pair of horizontally slidable bars 9-9. Both of 80 these bars are retained in their proper position by guide straps 10-10. Pivotally mounted on the side of the plate 8 is a pair of bell cranks 11-11, one having a link connection 12 with the upper bar 9, 85 and the other having a similar connection with the lower bar 9. To the forward end of the lower bar 9 is secured, in any appropriate manner, a pusher head 13 having a forwardly extending flange or angle 14 and 90 a rearwardly directed flange or leg 15. When the head 13 is in its retracted position, as shown in Figure 3, it will be noted that the flange 14 constitutes a stop for the bottles being received from the conveyor 3 and 95 when the head 13 is projected forward the feed of the bottles from conveyor 3 will be prevented or blocked by the flange 15. Detachably secured to the forward end of the upper bar 9 is a depending finger 16 which 100

at its lower end is provided with a pad or block 17 oppositely disposed with respect to the head 13 so as to clamp or firmly hold a bottle to said head.

- 5 Affixed to the under surface of the base 2 is a bracket 18 having oppositely extended trunnions 19 which pivotally support the transversely extending levers 20 and 21. The opposite end of said levers 20 and 21 are operatively connected by rods or links 22 to actuate the bell cranks 11. The lever 20, intermediate its end, has a laterally extending stud 20', upon which the roller 23 is rotatably supported and this roller 23 is adapted to have peripheral contact with a cam 24 securely affixed to the power shaft 25 of the machine. In order to effectively hold the roller 23 into constant active engagement with the peripheral surface of the cam 24 a tension spring 26 is secured at one end to the lever 20 and is suitably anchored as at 27 to some stationary part of the machine base or frame. The lever 21 is likewise provided with an intermediately positioned roller 28 which is adapted to ride within the grooved or flanged cam 29 which affords a positive movement in both directions to the lever 21, and, therefore, no spring or similar element is necessary to cause a retraction of this lever. This flanged cam 29 is also firmly attached to the power shaft 25.

The connecting links or rods 22 are made adjustable and by increasing or decreasing their length, any slight variation existing in the bar 9, link connection 12 or the bell crank 11 may be accounted for in order to maintain the proper distance between the bottle gripping members.

- 35 Briefly referring to the action of the machine it will be noted that the bottles are manually placed within the conveyor 3 and fed forward thereby to position the foremost bottle in front of the pusher head 13. Immediately after the bottle is so placed the upper bar 9 is moved through its link and lever connection by the cam 29 and this causes a slight rear or retracting movement to the grip pad 17 thereby effectively clamping or gripping the bottle. Both the pusher head 13 and the grip pad 17 are then simultaneously advanced to carry the bottle through the exit end of conveyor 3 and position the same on the step by step conveyor 6. In order to permit the full advancement of the grip pad 17 the side bars 7 of the conveyor 6 are cut away and when the bottle is properly positioned on the conveyor 6 the pad 17 continues in its forward movement so as to free the front surface of the bottle and at the same instant the pusher head 13 is rapidly retracted so as to withdraw the forwardly extending flange 14 from the subse-

quent path of movement of the bottle. After the bottle has been advanced by the step by 65 step conveyor the grip pad 17 is retracted so as to coact with the pusher head on the next bottle. During the forward projection of the bottle the rearwardly directed flange 15 on the pusher head 13 effectively blocks or 70 stops the forward feed of the bottles in the conveyor 3, but as soon as the head 13 is fully retracted the foremost bottle is fed to the face of head 13 and stopped in its proper position thereon by the forwardly extending flange 14.

I claim:

1. In a bottle transfer device comprising a reciprocatory plunger, a trough or guideway for delivering a bottle to the face of 80 the plunger, a gripping member disposed in parallel relation with respect to the face of the plunger and adapted to engage the bottle intermediate its top and bottom edges to clamp the bottle to the face of the plunger, 85 means for advancing the plunger and the gripping member with a bottle therebetween, and a second trough or guideway provided with means for removing the projected bottle. 90

2. In a bottle transfer device comprising a reciprocatory plunger having an angular offset at one side thereof to constitute a stop for the bottle, a trough or guideway for delivering a bottle to the face of the plunger, 95 a gripping member adapted to clamp the bottle to the face of the plunger, means for simultaneously advancing the plunger and the gripping member, and a second trough or guideway having means for removing the 100 projected bottle. 100

3. In a bottle transfer mechanism comprising a reciprocatory plunger, a gripping member disposed in parallel relation to the face of the plunger and coactive therewith 105 to hold the bottle in clamped position to the face of the plunger during forward movement of the latter, and means for moving the gripping member relative to the plunger at the termination of each movement of the 110 plunger. 110

4. A bottle feed mechanism comprising a plurality of bottle troughs or guideways, a transfer device arranged to convey the bottles from one trough or guideway to the 115 other, said device having a horizontally reciprocatory plunger and an opposed horizontally reciprocatory gripping face, said plunger and gripping face being arranged in spaced parallel relation and adapted in their 120 action to clasp a bottle therebetween, and means for actuating the transfer device.

In testimony whereof I hereunto affix my signature.

ARVID P. EKVALL.
